UNITED STATES PATENT OFFICE

ROBERT H. VAN SANT, OF CHICAGO, ILLINOIS

TOILET PACKAGE

Application filed April 2, 1928. Serial No. 266,572.

This invention relates to toilet articles and has for its principal object to provide an improved package containing a toilet preparation and an applicator. The preferred form 5 and arrangement is illustrated in the accompanying drawings in which—

Fig. 1 is an elevation;

Fig. 2 is a plan view and

Fig. 3 is a central vertical section taken on 10 the line 3—3 of Fig. 2.

This specific illustration and the correspondingly specific description are used for the purpose of making the disclosure full and clear and are not intended to impose such 15 limitations on the claims as would permit the substance of the invention to be used in other forms without infringement.

The container comprises a bottom 10 and a generally upright circular wall 11, together 20 forming what may be termed the body portion, and also a convex top 12 having a wall 13 telescoping with the wall 11. The telescoping walls are provided with complementary spiral corrugations 14 having the effect 25 of forming threads by which they are securely joined together.

The central portion of the convex top 12 is provided with a central discharge opening 15 surrounded by a flange 16. This flange and 30 the convex portion form a seat for an applicator such as the powder puff 17, which is of sufficient dimensions to overlap the convex top for a considerable area around the opening 15.

The cap comprises a central flat portion 18 corresponding roughly to the size of the discharge opening 15. A convex portion 19 and a marginal wall 20, which is corrugated at 21 to form threads cooperating with those 40 in the walls 11 and 13.

The powder puff 17 is of a yielding character and is pressed against the seat on the upper portion of the container by the cap and thus forms an inner closure and seal for the 45 container. The threaded connection between the wall 20 and the corresponding wall 11 of the container forms an outer seal. Thus the package is made practically secure against 50 the escape, not only of the powder or other

preparation, but of the aromatic constituents thereof.

The wall 11 extends a short distance above the convex wall 12, as shown at 22, and forms with the convex wall a sort of trough to catch 55 and contain powder that may be inadvertently dislodged from the puff upon the convex portion. Such powder is thus prevented from escaping down the sides of the container, or being lost on the dresser, or the 60 like.

The powder puff being considerably larger than the discharge opening 15, its marginal portion receives little or no powder and thus the user has much better control in applying 65 the powder to the skin.

In use the cap being removed and the puff being placed in the position shown in Fig. 3, the container is inverted and the powder thrown against the exposed portion of the 70 puff and the container returned to normal position. The puff is then used in the usual, or any suitable manner, and afterward is returned to its position on the convex top substantially as shown. The cap is then put on 75 and screwed down, effectively sealing the container. The puff being somewhat smaller than the area within the walls 22, no particular care is required in placing it on the top 80 preparatory to closing the package. The wall 22 unconsciously guides the user and assists in insuring that the puff will be properly placed.

I claim as my invention:

1. In a toilet package, a container having a convex top wall provided with a single comparatively large axial opening therein, the inner surface of said top wall sloping toward said opening, the marginal edge of said wall surrounding said opening being extended upwardly to form an upstanding flange, the side wall of said container extending upwardly beyond the top to form a continuous flange for preventing toilet material falling on said 90 top from sliding off the same, an applicator of substantially greater area than said opening adapted to be positioned on said flange and top wall over said opening, and a cap for said container for holding said applicator in 95 100

position on said flange for closing said opening.

2. In a package for containing toilet powder, a container having a top wall curved outwardly in cross-section and provided with a single relatively large axial opening, the inner surface of said top wall sloping toward said opening, an upstanding guard extending around said opening, an applicator on said guard and having its marginal edges extending a substantial distance outwardly of said guard all around the same, and a cap for said container for holding said applicator on said guard for closing said opening, said opening being of such an area that the amount of powder adhering to the puff will be sufficient for one application.

In testimony whereof I affix my signature.

ROBERT H. VAN SANT.
